(57) **CLAIM**

The ornamental design for a combined extendable ice fishing scoop and skewer, as shown and described.

DESCRIPTION

FIG. 1 is a front elevational view of a combined extendable ice fishing scoop and skewer showing my new design; FIG. 2 is a rear elevational view thereof; FIG. 3 is a left side view, the right side being a mirror image thereof; FIG. 4 is a top plan view thereof; and, FIG. 5 is a bottom plan view thereof. The pick on the bottom is removable (screws in). The handle is telescopic. It extends to different lengths.
